J. H. REEDY

DRIVING COLLAR

Filed May 27, 1920

UNITED STATES PATENT OFFICE.

JOHN H. REEDY, OF HAMILTON, OHIO.

DRIVING COLLAR.

Application filed May 27, 1920. Serial No. 384,616.

To all whom it may concern:

Be it known that I, JOHN H. REEDY, a citizen of the United States, and a resident of the city of Hamilton, in the county of Butler and State of Ohio, have invented a certain new and useful Driving Collar, of which the following is a full, clear, and exact description, reference being had to the drawings forming part of this specification.

10 My invention relates to clutch collars, to be used on shafting, for automatically grasping the desired shafts in a non-rotatable manner.

In paper winding machines having driven shafts over which the paper is to be wound, it is customary to employ suitable sleeves or cores, ordinarily of metal, slipped over the winding shafts, and to lock these sleeves to the shafts by means of a collar or collars 20 keyed into the shafts and employing set screws and the like to hold them in place.

The use of set screws is always dangerous and is the cause of a great many of the accidents in winding machines for paper or 25 the like, due to their catching the clothing and pulling the operator into the machinery.

The difficulty with doing away with set screws and keys is that the strain to be taken by the collars is so great as to render the 30 ordinary form of clamping collar entirely inadequate, so that my object is to provide a structure which will withstand the requisite working strains, and at the same time will be simple and effective in operation, and 35 which requires no key or key-way on the winder shaft.

I accomplish my objects by that certain construction and arrangement of parts to be hereinafter more specifically pointed out 40 and claimed.

In the drawings,

Figure 1 is an end elevation of the device.

Figure 2 is a longitudinal section thereof.

Figure 3 is a view illustrating the device 45 in use, and in a more compound form.

Figure 4 is a longitudinal section showing the frame portions only of the parts shown in Figure 2 but with an additional thrust resisting portion formed in connection with 50 the collar, said additional form being the one shown in Figure 3.

The device is made up in its simplest form of an inner and two outer members, and two

cage plates for a set of grasping rollers, said inner and outer members being made of a 55 size to loosely fit a shaft of the desired size.

The inner member 1, in the form selected for illustration in the drawings, is roughly triangular in shape at the outside and is cut on the inside with three cam faces 2, 60 terminating in shoulders 3, and tapering outwardly from the said shoulders.

The two outer members 4 are of the same outer shape and are fastened together with the inner member by means of screws or 65 bolts 5. The two outer members are formed internally into annular form, and are cut with cam shaped slots 6, three in number in this particular arrangement.

Set between the inner member and the two outer members are annular plates 7, which are loosely held so that they can slide in a rotary manner, due to cut away ledges 8, formed on the inner member. The plates 7 have closed slots 9 formed therein, in a direction radial to the center of the plates. 70

Three spirally grooved hard metal rollers 10, having spindles 11, 11, are mounted with their spindles extending through the slots 9, and thence into the cam shaped slots 6. 80 The peripheries of the rollers ride on the cam faces 2 of the inner member 1.

With the device constructed as above set forth, the two plates 7 form a freely moving cage for the gripping rollers 10 and the whole collar device can be slipped over a shaft, and will turn freely thereon in one direction, but in the other direction a movement of the shaft with relation to the collar will cause the rollers to ride up on the cam grooves 2, thereby clamping firmly and biting into the shaft. 90

Lugs 12 are formed on the outer members of the collar for engagement with whatever element is to be revolved by the shaft. 95 For example, in the case of a driven shaft 13, over which is slipped the sleeve or core 14 for rolling up paper 15, the core will have in engagement therewith a collar 16, loose on the shaft. This engagement may be by ribs 100 on the collar and slots in the core, or otherwise as desired. The collar 16 has notches therein for receiving the lugs 12 of one of the outer collar members of the novel device described, and thus the new clamping collar 105 will drive the core and wind up the paper.

on the same, after which it can be quickly and easily removed and the core slipped off.

As shown in Figures 3 and 4, one of the outer collar members may be formed with a sleeve portion 17, of larger internal diameter than the shaft to be engaged. This sleeve portion carries a controlling ring 18 threadedly thereon, which controlling ring has secured thereto an annular plate 19.

10 The annular plate engages rotatably a groove 20 formed in a bushing 21, of approximately the diameter of the shaft internally. The sleeve is grooved with slanting based grooves 22, on which ride small spirally cut rollers 23. The rollers are held in place by means of the bushing, which is movable longitudinally of the sleeve, by means of the controlling ring and has slots 23^a cut in its forward end, the outside edges 15 of which are cut away through a limited space as at 23^b to receive the spindles 24 of the rollers.

By adjusting the controlling ring, the inner bushing can be forced forwardly 20 through the sleeve, thereby forcing the rollers to ride up on the slanting groove bases and forcing them into engagement with such shaft as is lying within the device. When the rollers bite into the shaft there will be 25 a thrust receiving clamping action on the shaft, which will be increased in force upon a tendency to slip, due to the capability of the rollers to move along with their spindles in the cut-away portions 23^b behind the bushing slots.

With this compound structure it can be seen that both twisting strain and thrust strain will be taken care of, but that in spite of this the entire device can be quickly and 40 readily removed from its place by unscrewing the controlling ring, and tapping the device in a counter direction to the shaft movement. The feature of the cage element for the rollers enforces a simultaneous movement of all of them, thereby insuring tight engagement and ready removal.

I do not wish, by confining myself to the description of but two forms of my invention to exclude from the scope thereof the many 50 modifications which would amount mechanically to the same thing, but on the contrary I desire my claims that follow to be construed with the full benefit of the doctrine of equivalents.

Having thus described, my invention, what I claim as new and desire to secure by Letters Patent, is:—

1. In a driving collar for automatically clutching a shaft, the combination of an 60 element for engaging a shaft formed with roller clearance within it, comprising a series of circumferential cam grooves, a series of rollers set into said grooves and riding therein, and plates independently 65 movable with relation to the shaft and the

engaging element, for retaining the rollers in position and serving to cause their movement as a unit, said rollers constituting the sole grasping element between the shaft and the engaging element. 70

2. In a driving collar for shafts, the combination with a shaft engaging annular means, said means having a series of internal cam grooves, a series of rollers for the said grooves, and a cage loosely engaged with the shaft engaging means and acting as a retainer and spacer of the rollers, said rollers being adapted, upon revolution of a shaft with reference to the shaft engaging means, to travel in the cam grooves into a position of increasingly tight grip on such shaft and said cage being formed with slots for permitting movement of the rollers radially of the shaft. 75

3. In a driving collar for shafts the combination with an internal member, and two external members, said internal member having its internal face cut with circumferentially extending grooves having an inclined base, a series of rollers having spindles, cam shaped slots in the external members for said spindles, and cage means rotatably mounted intermediate the external members and engaging loosely the spindles of the rollers and spacing them apart, said rollers having roughened peripheries, and adapted to ride in the grooves on the bases thereof, for the purpose described and said cage being formed with slots for permitting movement of the rollers radially of the shaft. 80

4. In a driving collar for shafts, the combination with a shaft engaging annular means, said means having a series of internal cam grooves, a series of rollers for the said grooves, and a cage loosely engaged with the shaft engaging means and acting as a retainer and spacer of the rollers, said cage being formed with slots for permitting movement of the rollers radially of the shaft, said rollers being adapted upon revolution of a shaft with reference to the shaft engaging means, to travel in the cam grooves into a position of increasingly tight grip on such shaft, and said shaft engaging annular means having lugs thereon extending longitudinally of the said means, and adapted for engagement of a member to be revolved by the shaft. 100

5. The combination in a device of the character described of means to engage the shaft, said means comprising in part roughened rollers and cam means engaging the rollers to force them inwardly of the shaft engaging means upon relative rotary motion of the shaft and the means, and additional shaft engaging means unitary with the first mentioned engaging means, said additional engaging means comprising in part roughened rollers and cam means engaging the said rollers to force them into the shaft. 110

upon relative longitudinal movement of the shaft and the said additional engaging means.

6. In a driving collar for automatically clutching a shaft the combination of an element for engaging a shaft formed with a circumferential clearance within it comprising a series of circumferential cams, a series of roughened elements adapted to lie

within the said clearance and engage the cams, and cage means for retaining said roughened elements in interspaced relation to cause simultaneous movement thereof, said cage adapted to permit movement radially of the shaft of the roughened members. 15

JOHN H. REEDY.
